UNITED STATES PATENT OFFICE.

CHARLES C. SCHREIBER, OF CINCINNATI, OHIO, ASSIGNOR TO THE
L. SCHREIBER & SONS COMPANY, OF CINCINNATI, OHIO, A COR-
PORATION.

ELEVATOR-GATE.

SPECIFICATION forming part of Letters Patent No. 755,397, dated March 22, 1904.

Application filed January 6, 1904. Serial No. 187,863. (No model.)

To all whom it may concern:

Be it known that I, CHARLES C. SCHREIBER, a citizen of the United States, residing at Cincinnati, in the county of Hamilton and State 5 of Ohio, have invented certain new and useful Improvements in Elevator-Gates, of which the following is a specification.

My invention relates to a device for closing elevator-doors in which two parallel doors 10 moving in the same direction are employed to close the cab-opening, both doors passing behind the partition, one door—the front door—to travel at twice the speed of the rear door.

The object of my invention is to provide a 15 cheap, durable, and easy mode of accomplishing this result, the features of which are more fully set forth in the description of the accompanying drawings, forming a part of this specification, in which—

20 Figure 1 is a front elevation looking from the inside of the shaft of the top section of the doors and the door-moving devices. Fig. 2 is a side elevation of the pair of door-supporting devices. Fig. 3 is a central vertical 25 section on line $\alpha\alpha$; Fig. 1.

A represents the door-posts of the cabway. B represents a stationary panel.

C represents the rear door, and D the front door.

30 C' represents the top frame-piece of the rear door.

G represents a gooseneck-bracket arm rigidly secured to the top frame of the door.

H represents a roller journaled in the gooseneck-bracket. I represents a track on which said roller runs. There are preferably two such roller-supports to a door.

40 D' represents the top frame-piece of the front door. K represents a gooseneck-bracket rigidly secured to the same. L represents a roller journaled to said bracket, as shown in Fig. 2.

45 M represents a track, tracks M and I being parallel and arranged one in front of the other and spanning the cabway.

Journalized to each of the posts A A are sprocket-wheels O P, both revolving on the same axis α . The sprocket-wheel O is twice the diameter of the sprocket-wheel P.

R represents an endless sprocket-chain engaging and traveling over the sprockets O. 50

S represents an endless sprocket-chain engaging with the sprockets P.

b represents stubs rigidly secured to the top of gooseneck G and for projecting upward and 55 engaging the links of the sprocket-chains S.

c represents a stub rigidly secured to the gooseneck K at the appropriate place to project into and engage the length of the sprocket-chain R. 60

a represents the stud on which the differential pair of sprocket-wheels is journaled.

d represents a washer journaling on said shaft, and e a pin for holding said sprocket-wheels upon their axis. 65

For convenience of construction the sprocket-wheel P has a hub. The entire length of the axis and the sprocket-wheel O seats upon the front end of the hub and is keyed thereto by the feather h , so that both wheels 70 must move in unison.

Mode of operation: It will be observed that the sprocket-wheel O is twice the diameter of the sprocket-wheel P. Consequently the chain traveling on the sprocket-wheel O will move 75 at twice the speed of the chain of sprocket-wheel P. The operation of the door-closing device is very simple and obvious. The elevator attendant takes hold of the front door after the fastening-catch has been released and 80 gives it a slight pull which starts the sprocket-wheel in motion, and they will readily and easily run back into position, one door passing behind the other door and both behind the stationary panel. A slight pull on the front 85 door when in a closed position will start them in motion, and they will move forward and come in closed position, when they may be secured by a catch or other appropriate means. The above device is exceedingly simple and 90 effective and is inexpensive as well as durable.

I have shown and described a sprocket-wheel and sprocket-chain which I deem the simplest and best mode but any link belt with appropriate carrier is the equivalent thereof. 95

Having described my invention, I claim—

1. In an elevator-door a pair of tracks, two door members slidably mounted on said track

respectively, two wheels, an endless carrier connecting them fixed to one of said door members, two wheels being of different diameter than the first-named wheels, an endless carrier connecting them, fixed to the other door members and journal-supports for said wheels, means connecting the first-named pair of wheels and, means connecting the second-named pair of wheels, substantially as described.

2. In an elevator-door a pair of tracks, two door members sliding thereon respectively, two shafts fixed above the casing upon opposite sides of the doorway, upon each shaft a pair of wheels which are of different diameter fixed to rotate in unison, the said wheels being situated so that two of them turn in the plane of one door movement and two of them turn in the plane of the other door movement, and endless carriers connecting the wheels in the same plane and also connected to said door members respectively, substantially as described.

3. A pair of endless-belt carriers of different sizes secured together and mounted upon a common shaft, with a second pair at the opposite side of the elevator-shaft, two door members and connections from said door members one to the larger and one to the smaller carrier, substantially as described.

4. In combination with two door members sliding in parallel planes, a pair of wheels of different diameter fixed to rotate in unison in the respective planes of travel of said two door members, a duplicate set of wheels, and two endless carriers connecting the wheels in the same plane, one door member being fixed to one carrier and the second door to the other carrier, substantially as described.

5. In combination with two differentially-traveling door members sliding in parallel

planes, parallel tracks in the frame, rollers riding on said tracks and supporting said door members respectively, two pairs of wheels differing in diameter journaled on each side of the frame, each pair being fixed to rotate in unison, one member of each pair turning in the planes of said door members, endless carriers connecting the wheels in the same plane, and connections between the doors and the endless carriers, substantially as described.

6. In a doorway, parallel tracks, rollers thereon, two door members supported by said rollers and slideable in parallel planes, a pair of wheels of different diameter fixed to rotate in unison, said wheels being journaled on the door-frame with its members in the respective planes of the parallel tracks, a duplicate pair of wheels journaled on the other side of the door-frame, an endless carrier connecting the two wheels of the same plane fixed to one of said door members, and a second endless carrier connecting the two wheels fixed to the second door member, whereby when said doors are slid in either direction they travel at differential speeds, substantially as described.

7. A door-operating device comprising parallel tracks, door members sliding thereon respectively, wheels of different diameter fixed to rotate in unison in the planes of the door members respectively, said wheels being supported on the casing, and transmitting devices between each wheel and its respective door member, whereby one of said doors is caused to be moved faster than the other, substantially as described.

In testimony whereof I have hereunto set my hand.

CHARLES C. SCHREIBER.
